UNITED STATES PATENT OFFICE

GEORGE J. BLUM, OF CHICAGO, ILLINOIS

DESIGN FOR AN AUXILIARY IMPACT DEVICE FOR AUTOMOBILE BUMPERS

Application filed March 27, 1933. Serial No. 47,602. Term of patent 7 years.

To all whom it may concern:

Be it known that I, GEORGE J. BLUM, a citizen of the United States, residing at Chicago, in the county of Cook and State of Illinois, have invented a new, original, and ornamental Design for an Auxiliary Impact Device for Automobile Bumpers, of which the following is a specification, reference being had to the accompanying drawing, forming part thereof.

Figure 1 of the drawing is a front elevational view of an auxiliary impact device for automobile bumpers, showing my new design.

Fig. 2 is a side elevational view of the device, fastening bolts being shown in broken lines.

Fig. 3 is a transverse sectional view taken approximately in the plane of line 3—3 of Fig. 1.

I claim:

The ornamental design for an auxiliary impact device for automobile bumpers, substantially as shown.

GEORGE J. BLUM.
